UNITED STATES PATENT OFFICE.

GEOEGE H. KNOWLES, OF DULUTH, MINNESOTA.

INTERNAL-COMBUSTION ENGINE.

1,257,248.

Specification of Letters Patent. Patented Feb. 19, 1918.

Application filed April 3, 1917. Serial No. 159,492.

To all whom it may concern:

Be it known that I, GEORGE H. KNOWLES, a citizen of the United States, residing at Duluth, in the county of St. Louis and State of Minnesota, have invented new and useful Improvements in Internal-Combustion Engines, of which the following is a specification.

This invention relates to internal combustion engines and particularly the valves and valve mechanism, the engine being of the four-cycle type and the valve mechanism embodying a plurality of tubular telescopically related members which together with the engine and valve chamber are so ported and the movements thereof are so timed, that in each complete cycle of the engine, the intake ports will register at the proper period, the same being true with regard to the exhaust ports.

A further object of the invention is to combine the tubular valve members, and so construct the same that they will mutually guide and direct each other so as to insure the proper registration of the ports of said valve members.

A further object of the invention is to provide valve members of the character referred to, and a valve casing or chamber of such formation that in conjunction with an oil feed pipe or conduit, said valve members act as a force feed means for lubricating said valve members and the casing or chamber in which they operate. The said force feed lubricating means may also be used for supplying lubricating oil to other parts of the engine requiring lubrication.

With the above and other objects in view, the invention consists in the novel construction, combination and arrangement of parts, herein described, illustrated and claimed.

In the accompanying drawings:—

Figure 1 is a sectional view of the engine, taken diametrically of one of the cylinders and the respective valve casing or chamber, showing the valve members partly in elevation and partly in section.

Fig. 2 is a cross section on the line 2—2 of Fig. 1.

Fig. 3 is a bottom plan view of the valve members.

Figs. 4 to 9 inclusive are detail views illustrating the valve members and the consecutive relative positions or movements thereof.

Fig. 10 is a plan view of the valve operating shaft.

In the drawings, I have illustrated only one cylinder of an engine and the valve mechanism used in conjunction with said cylinder. It is to be understood however that the valve mechanism hereinafter particularly described may be used in conjunction with any number of cylinders, there being one valve unit for each cylinder and each valve unit operating both as an intake valve and an exhaust valve for its respective cylinder.

1 designates the engine cylinder having located at one side thereof a valve chamber or casing 2. In the preferred embodiment of the invention the valve casing 2 is formed integrally with the cylinder and communicates therewith by an intake port 3 and an exhaust port 4, the intake port 3 being located adjacent to the cylinder head 5 and the exhaust port or passage 4 preferably extending through the head as shown in Fig. 1, thereby obtaining a more thorough scavenging action. The valve casing 2 is provided directly opposite the intake port 3 with a corresponding intake port 6 and is also provided directly opposite the exhaust port or passage 4 with a corresponding exhaust port 7. 8 designates a combined intake and exhaust manifold, comprising the intake passage 9 and the exhaust passage 10. The valve casing 2 is closed at one end by a head 11 the purpose of which will herein-after appear.

The valve unit comprises a tubular valve member 12 having an accurate sliding fit in the casing 2 and also comprises another tubular valve member 13 which has an accurate sliding fit in the tubular valve member 12, said valve members 12 and 13 being telescopically related to each other and both of them being slideable longitudinally within the casing 2, the bore 14 of which is cylindrical. The larger or outer tubular valve member 12 is formed in the opposite sides thereof with transversely elongated inlet ports 15 and is also formed in the opposite walls thereof with exhaust ports 16, the ports 15 and 16 being in spaced relation to each other. The inner tubular valve member 13 is also provided in opposite sides thereof with transversely elongated inlet ports 17 and is further provided in the oppo-

site walls thereof with transversely elongated exhaust ports 18, the ports 17 and 18 being in spaced relation to each other but arranged closer together than are the ports 5 15 and 16 of the outer valve member 12.

As shown in Fig. 1, the ports 15 and 16 of the valve member 12 are located at the same distance apart as the ports 3 and 4 and at the same distance apart as the ports 6 and 10 7, all of which ports have been previously referred to. The ports 17 and 18 of the valve member 13 are however located closer together than the ports 4 and 5 and the ports 6 and 7 so that only one of the ports 17 and 15 18 may register at one time with one of the ports 15 and 16 of the outer tubular valve member 12. One end of the inner tubular valve member 13 is closed by a head 19 at that end adjacent to the closed head 11 of 20 the valve casing 2.

The valve member 12 is cut away at 20 leaving only a semicylindrical extension 21 having formed on the inner extremity thereof a laterally projecting boss 22 terminating in a flat machined face 23 against which abuts one end of a connecting rod 24 the other end of which is connected to a cam or eccentric shaft 25 which is connected by gears to the crank shaft 26 of the engine 25 so that the shaft 25 will be driven at one-half the speed of the crank shaft 26. The inner tubular member 13 is likewise provided at its inner extremity with a laterally extended boss 27 terminating in a flat machined face 28 against which bears one end of another connecting rod 29, said rod being connected at its opposite end to another crank or eccentric on the shaft 25. The connecting rods are attached to the valve members 12 and 13 by journal pins 30 and the cranks or eccentrics 31 and 32 of the shaft 25 are set 45°, more or less from each other so as to cause the proper reciprocatory movements of the valve members 12 and 13 35 controlled thereby. The valve members 12 and 13 and the actuating means therefor are so designed that in each complete cycle of operation of the engine, the intake ports hereinabove referred to are brought into 40 registration with each other and at another period, the exhaust ports are all brought into registration with each other, this being necessary to adapt the engine to operate on the four-cycle principle. The inner end portion of the tubular valve 12 is formed with an arcuate and substantially semicircular reinforcement or relatively thickened wall portion 33 terminating in oppositely located guiding shoulders 34 which extend longitudinally of the valve member 13 and ride against the correspondingly disposed shoulders 35 on the valve member 12 formed by cutting away the valve member 12, at 20, as above described. The shoulders 34 and 60 35 form guiding means and in this way the

valve members 12 and 13 mutually guide each other, produce a smooth and accurate sliding action between said members and insure the proper registration of the ports of said members throughout the entire area of 70 said ports.

36 represents an oil feed pipe which may lead from the crank case of the engine or other point of oil supply to the head of the valve casing 2, said pipe or conduit leading through the closed head 11 of said valve casing as shown in Fig. 1. The pipe or conduit 36 has incorporated therein a regulating valve 37 so that the flow of lubricating oil to the valve casing 2 may be accurately 80 gaged or regulated, and said pipe or conduit also embodies a check valve 38 to prevent the return flow of the oil. Between the regulating valve 37 and the head 11 of the valve casing 2, the pipe or conduit 36 85 may be provided with a branch pipe 39 and the last named pipe may lead to any part or bearing of the engine or its equivalent requiring force feed lubrication. As the inner valve member 13 is closed by the head 19 and as said valve member 13 fits snugly within the outer tubular valve member 12, in the reciprocatory movements of said valve members, oil also drawn into the valve casing 2 between the head 11 and the adjacent 90 ends of the valve members 12 and 13. This insures perfect lubrication of the valve members and the wall of the valve casing 2 and by the same means, oil may be forced through the branch pipe 39 to various other 95 points as may be deemed expedient. The water jacket 30 surrounds the wall of the combustion chamber of the cylinder and also surrounds the major portion of the wall of the valve chamber 2 and extends along the 100 opposite sides of the intake and exhaust ports or passages 3 and 4, thereby keeping the parts referred to cool, and preventing overheating thereof. This together with the perfect lubrication of the valve members 110 and the valve casing, maintains the valve members in prime working condition causing them to operate silently and with a minimum amount of friction. The outer tubular valve member 12 is shown as surrounded by packing rings 41 arranged at 115 opposite sides of each of the ports 15 and 16. While this is desirable in some cases, in actual practice it has not been deemed an essential feature, as after six months' duty, 120 an engine embodying the valve mechanism hereinabove described has been found to increase rather than decrease in its compression and power efficiency. The valve members remain comparatively cool and are perfectly lubricated at all times.

The valve mechanism hereinabove described may be manufactured cheaply and maintained economically as the valve members are practically of uniform diameter 130

throughout, excepting only for the offset bosses at the inner ends thereof and the reinforcement 33 of the valve member 13. On account of the simple arrangement of 5 the ports, a direct and free movement or flow of the incoming charges and the outgoing exhaust is provided for, this being one of the most important features in an internal combustion engine as it imparts increased power efficiency to the engine and 10 prevents the rapid accumulation of carbon in the cylinders.

I claim:—

1. In an internal combustion engine, the combination of a cylinder, and a combined intake and exhaust valve unit embodying a valve casing having communication with said cylinder through an intake port and an exhaust port arranged in spaced relation to 15 each other, said valve casing having complementary intake and exhaust ports directly opposite the first named intake and exhaust ports, an outer tubular valve member mounted to reciprocate in said casing and formed 20 in the walls thereof with oppositely located intake ports and with oppositely located exhaust ports arranged at the same distance apart as the aforesaid intake and exhaust ports, an inner tubular valve member slid- 25 able within the first named valve member and having intake ports directly opposite in the side walls thereof and also having exhaust ports directly opposite in the side walls thereof, the intake and exhaust ports 30 of the inner tubular member being arranged closer together than the corresponding ports of the outer tubular member, a crank shaft driven valve actuating shaft, and operating means between the last named shaft and 35 said valve members, operating to reciprocate said valve members out of unison.
2. In an internal combustion engine, the combination of a cylinder, and a combined intake and exhaust valve unit embodying a valve casing having communication with said cylinder through an intake port and an exhaust port arranged in spaced relation to 40 each other, said valve casing having complementary intake and exhaust ports directly opposite the first named intake and exhaust ports, an outer tubular valve member slid- 45 able within the first named valve member and having intake ports directly opposite in the side walls thereof and also having exhaust ports directly opposite in the side walls thereof, the intake and exhaust ports of the inner tubular member being arranged closer together than the corresponding ports of the outer tubular member, a crank shaft driven valve actuating shaft, and operating 50 means between the last named shaft and said valve members, operating to reciprocate said valve members out of unison, the outer valve member being cut away at one end to leave 55 diametrically opposite longitudinally extending guide shoulders, and the inner valve member being formed with corresponding shoulders which work in sliding contact with the shoulders of the outer valve member.

ports, an inner tubular valve member slide- 60 able within the first named valve member and having intake ports directly opposite in the side walls thereof and also having exhaust ports directly opposite in the side walls thereof, the intake and exhaust ports of the inner tubular member being arranged closer together than the corresponding ports of the outer tubular member, a crank shaft 65 driven valve actuating shaft, and operating means between the last named shaft and said valve members, operating to reciprocate said valve members out of unison, said valve members having longitudinally ex- 70 tends diametrically opposite abutting shoulders whereby said valve members mutually guide each other and insure perfect registration of the intake and exhaust ports of both valve members.

3. In an internal combustion engine, the combination of a cylinder, and a combined intake and exhaust valve unit embodying a valve casing having communication with said cylinder through an intake port and an exhaust port arranged in spaced relation to each other, said valve casing having complementary intake and exhaust ports directly opposite the first named intake and exhaust ports, an outer tubular valve member mounted to reciprocate in said casing and formed 80 in the walls thereof with oppositely located intake ports and with oppositely located exhaust ports arranged at the same distance apart as the aforesaid intake and exhaust ports, an inner tubular valve member mounted to reciprocate in said casing and formed 85 in the walls thereof with oppositely located intake ports and with oppositely located exhaust ports arranged at the same distance apart as the aforesaid intake and exhaust ports, an inner tubular valve member slid- 90 able within the first named valve member and having intake ports directly opposite in the side walls thereof and also having exhaust ports directly opposite in the side walls thereof, the intake and exhaust ports of the inner tubular member being arranged closer together than the corresponding ports of the outer tubular member, a crank shaft driven valve actuating shaft, and operating 95 means between the last named shaft and said valve members, operating to reciprocate said valve members out of unison, the outer valve member being cut away at one end to leave 100 diametrically opposite longitudinally extending guide shoulders, and the inner valve member being formed with corresponding shoulders which work in sliding contact with the shoulders of the outer valve member.

In testimony whereof I affix my signature.
GEORGE H. KNOWLES.
